BOTTLE

Morris L. Holtz, New York, N.Y., assignor to Haig and
Haig Limited, Markinch, Fife, Scotland

Filed July 8, 1959, Ser. No. 56,700

Term of patent 14 years

(Cl. D58—6)

Fig. 1.

Fig. 2.

Fig. 3.

Fig. 4.

Fig. 5.

Fig. 6

Fig. 1 is a perspective view of a bottle, showing my new design;

Fig. 2 is a side elevational view thereof;

Fig. 3 is a side elevational view of the bottle rotated 90° from the position shown in Fig. 2;

Fig. 4 is a top plan view thereof;

Fig. 5 is a bottom plan view thereof; and

Fig. 6 is a cross sectional view through the center of the body portion thereof.

I claim:

The ornamental design for a bottle, as shown.
